LADY'S DRESS GARMENT

Charlotte Goldstein, New York, N. Y., assignor
to Laurel Fashions, Inc., a corporation of New
York

Application October 14, 1948, Serial No. 54,373

10 Claims. (Cl. 2—105)

1

My present invention relates to ladies' garments and while shown embodied as a lady's blouse is also applicable to ladies' dresses, and suits.

It is among the objects of this invention to provide a lady's blouse that may be readily fashioned by stitching together a small number of pattern-cut blanks of fabric which have special fabric parts so conformed and arranged as to admit of great versatility for a great variety of different attractive style effects in the manner of wear of one and the same garment, such effects including among many others, that of a blouse with a V-neck, a turtle neck, a shawl collar, a petal leaf collar, a floating collar, a bow tie, a twin twisted lateral bow, twin buds and a jabot.

Another object is to attain many of numerous possible style effects in the manner of wear of one and the same blouse and this without equipping the garment with fasteners of any character whatsoever and without resort to stitching, but by simply draping or arranging, folding or inter-folding, knotting or inter-knotting, or tying the special fabric elements of the garment and to attain any of numerous other style effects with the aid of an ordinary pin and any of numerous still further style effects by correlating the special fabric parts of the garment with articles of costume jewelry commonly worn by womankind.

According to the invention the blouse, which may otherwise be of any of various conventional types is characterized by a pair of wedge-shaped wings or flaps which are so constructed and so arranged at the neck line of the garment as to admit of being draped, folded or inter-folded, knotted or inter-knotted, or so correlated by the wearer with costume jewelry as to produce any of a multiplicity of different style effects, each of which effects the wearer can produce without assistance in a few seconds, upon donning the garment.

In the accompanying drawings in which are shown one or more of various possible embodiments of the several features of the invention:

Fig. 1 is a perspective view showing the donned garment in one of its numerous modes of wear.

Fig. 2 is a plan view of the garment as laid flat upon a table.

Fig. 3 is a plan view of the pattern-cut blanks from which the garment is fashioned.

Fig. 4 is a perspective view of the garment adjusted for a bow tie effect.

Fig. 5 is a view similar to Fig. 4 adjusted for a Russian blouse effect.

Fig. 5a is a rear view of the embodiment of Fig. 5.

2

Fig. 6 is a view similar to Fig. 4 of the garment adjusted for a turtle neck effect.

Figs. 7 to 13 inclusive each shows a distinct style of blouse fashioned by the wearer by draping, folding, knotting, tying or other adjustment of the garment shown in Figs. 1 to 3.

Fig. 14 is a view similar to Fig. 4 showing an illustrative mode of wear of the garment of Figs. 1 to 3 with aid of an ordinary pin and,

10 Figs. 15 to 25 inclusive each shows a distinct style of blouse draped by the wearer in connection with one or more articles of costume jewelry that serves to support or retain the garment of Figs. 1 to 3 in the particular draped condition shown.

15 Referring now to the drawings, the garment in one of its preferred embodiments is made up of a number of pattern-cut blanks of suitable fabric such as nylon, silk, rayon or cotton which may be of plain color or of any design. The blanks comprise a back panel 30 and two identical front panels 31 and 32.

20 The back panel is of more or less conventional shape and has a rear neck edge 33, sloping shoulder edges 34, curved side edges 35 and arm hole edges 36, intervening between the shoulder and side edges. Preferably the back panel is shaped by folding inward along two pairs of dot and dash lines 38 rising from the lower edge 37 and stitching together along upright dart lines 39.

25 Each of the two identical panels 31, 32 making up the front of the garment has a shoulder edge 40, an arm hole edge 41, below which extends the side edge which includes a curved upper portion 42, a short horizontal portion 43 and an upright edge 44. The fabric of each front panel is desirably folded inward along dot and dash lines 45 extending obliquely from edge portions 42 and 43 and stitched together to form a dart 46. The curved edge 42 being brought by the dart into alignment with the upright edge 44, the side edge 42, 44 is now stitched along its full length to the corresponding curved side edge 35 of back panel 30. The corresponding shoulder edges 34 and 40 of rear and side panels are stitched together. The side edges 47 opposed to edges 44 of the two identical front panels are stitched together (preferably before stitching to the back panel), thereby forming a median upright seam 48 (Fig. 2) at the front of the garment, which seam extends from the lower edge 49 to the lower end or vertex 50 of the generally V-shaped neckline of the garment. Preferably

30 a narrow arcuate facing strip 51 is stitched along the inner face of the rear neck line 33.

35 The garment which as thus far described is substantially conventional is of course suitably

hemmed in manner obvious and that need not be described.

According to the invention a wedge shaped elongated wing or flap 51 extends obliquely outward from and preferably as a part integral with that upper corner of each front panel 31, 32 which is at the midline of the garment. Substantially the entire width of the root of each wing extends along the corresponding side of the V-shaped neckline. Desirably as shown, one edge of the wing extends as a slight S or ogee curve 52 generally upward and outward from the vertex 50 of the neckline, which presents a V-shaped neckline when the garment is donned substantially as shown in Fig. 1 and the wings allowed to hang freely. The other edge 53 of each wing extends straight and nearly parallel to and somewhat below the shoulder edge 40 of the panel, a curved edge 54 at the root end of the wing edge connecting it to the neck end 56 of the shoulder edge 40. The lateral edges 52 and 53 of each wing intersect at an acute apex angle or point 55. Desirably, the length of the wing is at least equal to the width of its root shown by the dotted line extending from 50 to 56 in Fig. 3 and the extremities of said edge 52 are nearly equidistant from point 50.

When the garment is laid on a table as nearly flat as possible, the wings 51 rise as shown in Fig. 2, directly upward from the vertex 50 of the V-shaped neckline at which their roots are connected together. The edges 52 which are the inner edges of the two wings lie in juxtaposition in substantial alignment with the central upright seam 48 as shown in Fig. 2, and the other or outer edges 53 of the wings extend obliquely upward from the respective shoulders.

The wings are of length such as to admit of being tied at their ends in back of the neck in some of various possible effects to be described below. For all these effects, the vertex 50 of the V-shaped neckline from which the wings rise is preferably approximately 7 inches below the neck end of the shoulder seam, and the wing rises approximately ten or eleven inches or more from said neck end. The entire inner upright edge 52 of the wedge shaped wing, from the vertex 50 to apex 55 may be about 18 inches long. In practice the distance from the point 56, (the inner or neckline end of the shoulder seam) to the point 50 (the vertex end of the neckline) is about eleven inches and the distance from said point 56 to the apex 55 of the wing is approximately the same length but preferably an inch or so longer. All of the foregoing dimensions would be decreased for the smallest size of blouse and increased for the largest of the three sizes in which the garment is usually made and are set forth herein for completeness of disclosure and not by way of limitation.

Preferably the front panels 31 and 32 are bias cut as suggested in Figs. 2 and 3, and since the wings 51 do not extend at a 45 degree angle to the length of said panels, the fabric thereof also is somewhat on the bias for a purpose that will more fully appear hereinafter.

In order to afford sufficient weight or body and the needed finish to both faces of the wings 51, each of said wings is equipped with a liner 57 desirably of the same fabric and color as the rest of the garment, but optionally of different fabric, color or design, stitched in place along the entire vertical inner edge 52 and oblique outer edge 53 of the corresponding wing but the root

edge of said liner 57 is preferably unattached between its ends.

The structure of the garment with its special wings having been described, some of the numerous modes of wear thereof will now be briefly set forth.

Fig. 1 shows the garment as donned, with each wing folded longitudinally outward along line 58 and with the pointed end 59 thereof obliquely folded forward and depending from fold line 60 to produce the effect of short wings over-lapping and depending from the upper oblique edges of a pair of lapels that define a V-neck rising from the vertex 50.

In Fig. 4 the two wings are shown loosely knotted together near their root ends adjacent the front of the neck at 61 with the points 62 of the wings hanging laterally from the knot, and the neck substantially closed. The effect is that of a bow blouse.

In Fig. 5 the wings are folded one over the other, obliquely upward and rearward about the neck as at 62 and their points are tied together as at 63 in Fig. 5a at the rear of the neck. A Russian blouse effect is thus produced at the front as shown in Fig. 5.

In Fig. 6 the entire length of each wing is twisted as at 64, the twisted wings are drawn around the neck and their points are tied together as at 63 in Fig. 5a at the rear of the neck, to produce a closed collar effect.

In Fig. 7 the pendant wings are reversely coiled vertically for their outer edges 53 to extend each as a loop laterally of the neck line vertex 50 and the points of the wings are tied together as at 65 slightly above the vertex 50 to produce still a different effect.

In Fig. 8 the wings are folded inward at the V-neck, draped longitudinally upward and tied together in back of the neck at their points just as in Fig. 5a to produce an open V-collar effect.

In Fig. 9 the wings are longitudinally folded at 66 along the neckline to produce a lapel collar effect and their points are tied together at the rear of the neck, again as in Fig. 5a.

In Fig. 10 each of the wings is loosely knotted near its root as at 67 at the front to produce a bud effect with the point 68 of each wing hanging downward in the manner of a leaf, the twin buds flanking the open V-neck.

In Fig. 11 each wing is coiled as a scroll 69 to flank the open V-neck for still another effect.

In Fig. 12 one of the wings is folded as a collar 70 about the neck and the other is draped obliquely upward at 71, the two wings being tied together near their points at the back of the neck to produce a turtle collar effect.

In Fig. 13 the point end 72 of each of the wings is coiled under the root part 73 of the wing in pendant position along the oblique bending line 74 with said pointed ends 72 crossing in superposed relation for another V-neck collar effect.

In Fig. 14 one of the wings illustratively that at the right is twisted lengthwise and its ends are pinned together to form a rope ring 75 lying against the body at the neck, through which ring the other wing 76 is passed to depend therefrom.

In Fig. 15 the wings are drawn upward through a necklace and turned downward over the necklace and reversely folded upward, with the points 79 of the wings depending from the front in a closed neck ruff collar effect.

In Fig. 16 one of the wings is folded in back of the collar along fold line 80 and tucked under

the back of the garment, while the other wing 81 is passed through a necklace to hang from one side thereof in a petal effect.

In Fig. 17 a jewelry ring 82 is used through which both wings are passed, the ring being drawn upwardly as far as it will go frictionally to be held adjacent the neck by the bunching of the wing roots therein, the main length of the wings hanging downward from the ring as at 83.

In Fig. 18 a ring 82 is similarly used with both wings directed toward one side, so that while the ring embraces the root of wing 84, it embraces a part well above the root of wing 85. Substantially the full length of wing 84 thus hangs from the ring while the shorter and correspondingly stiffer protruding end of wing 85 extends more nearly horizontally.

In Fig. 19 the V-neck is drawn substantially closed and the main length of each wing 86 is drawn upwardly through a necklace to hang downward therefrom for another effect.

In Fig. 20 the wings are loosely tied together immediately below the neck as at 87 to close the V-neck for their pointed ends to extend laterally as at 88, one at a higher level than the other, and said pointed ends 89 may be held in place by costume jewelry pins 89 illustratively shown connected by a chain 90.

In Fig. 21 the two wings are turned upwardly at each side of the neck directly under a necklace, exposing the necklace therebetween and are then drawn outward transversely around the necklace as at 86 for the effect of an interrupted ruffled collar with the V-neck exposed below the necklace.

In Fig. 22 the inner edges 52 of the two wings are brought together in side by side abutting relation at the front and are pinned in place by stick pins 87 to afford a jabot effect.

In Fig. 23, one of the wings 88 is folded in back of the neck for a closed neck effect while the other wing is coiled into a cornucopia at the bosom and its pointed end 89 is attached by a brooch 90.

In Fig. 24 each wing is folded back for a lapel effect at 91 and then reversely curved over the collar bone in a shoulder loop 92, the end of which extends over the shoulder, the two ends being tied together in back. The trough of each open loop is attached to the front of the garment by a brooch 93.

In Fig. 25 the wings are passed under a necklace, tied together at the front as at 94, the rear ends are tied together behind the neck and the main areas are flared laterally as at 95 over the necklace for a floating collar effect.

The drawings thus show twenty-two (22) typical style effects in addition to that of Fig. 1 in which the blouse shown in Figs. 1, 2 and 3 may be worn.

The blouse though devoid of buttons, fastening hooks, slide fasteners or the like is thus shown to admit of the numerous effects illustrated in the drawings, each of which is readily produced by draping, folding or knotting the individual wings, or by interfolding or interknotting and tying the wings as described. Many of these effects as for instance those of Figs. 4 to 13 inclusive are produced without resort to any extraneous securing or holding means. Additional style effects such as that of Fig. 14 are shown to be produced with the aid of a single pin. The style effects of Figs. 15 to 25 are produced as described with the aid of costume jewelry. For none of these effects is any stitching required or need

the blouse be made with fasteners such as snap fasteners, slide fasteners or the like. Each of the effects is produced in but a few seconds by the wearer herself after the garment has been donned and by simple manipulation of the wings in the manner above set forth and without assistance.

In each of those embodiments in which the pointed end of one or both wings is exposed to view, as for instance in Figs. 4, 10, 11, 13 to 20 inclusive, 22 and 23, the slightly bias cut wing with its inner curved or ogee shaped edge 52 and its outer straight edge 53 automatically drapes itself in a graceful asymmetrical leaf-like effect that contributes substantially to the style of the garment in wear.

The multifarious style effects shown in the drawings are merely illustrative of forty (40) or more possible style effects to which one and the same garment of Figs. 1 to 3 lends itself.

No particular novelty is claimed for the appearance of the garment in any one of the style effects shown in the drawings, but such effects individually have heretofore been produced only in relatively costly models. For instance, the twin bud embodiment of Fig. 10 has heretofore required separate fabrication of the bud to be stitched to the face of the blouse. This is also true of the bow of the embodiment of Fig. 4. The production of the twisted neck effect of Fig. 6 has involved the special skill of expert designers and skilled operatives and the same is true of many of the other effects.

It will be understood that the particular pattern of sleeveless, slip-over blouse shown in Fig. 3 is largely illustrative of the invention. The wedge shaped wings may be incorporated in any of numerous possible styles of blouses of known type including blouses of front closure and back closure, loose fitting and tight fitting types, with and without sleeves.

It is also understood that the garment substantially as shown could be combined with a skirt in various embodiments of ladies' dresses, and suits.

By reason of the very wide choice in the style of wear to which it is so readily adapted, the garment affords a variety of effects for formal and informal wear that spells economy and the garment by virtue of its versatility is one of which the wearer is not likely soon to tire.

As many changes could be made in the above garment, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A lady's garment of the character described having a front presenting a V-shaped neckline, a pair of substantially pointed wings unitary with said front, each wing having a root substantially the entire width of which extends along the corresponding side of said V-shaped neckline, said wings being of length such as to admit of tying their pointed ends together at the back of the neck.

2. A lady's garment of the character described, having a back panel, and a front panel connected at the outer portions of their upper edges, the intervening portions of the upper edges of said

panels being unconnected and determining a V-shaped neckline, and a pair of adjacent wedge-shaped elongated wings symmetrically arranged at the midsection of the front panel, each wing having a root, substantially the entire width of which extends along the corresponding side of said V-shaped neckline, one edge of each of said wings being substantially continuous with and rising in the flattened garment from the center line of the front panel and the other edge rising obliquely from substantially the inner or neckline end of the corresponding connection between the upper edges of the panels.

3. A lady's garment of the character described, comprising a back panel, and a front panel connected at the outer portions of their upper edges, the intervening portions of the upper edges of said panels being unconnected and determining a V-shaped neckline, the front panel having a pair of elongated wedge shaped wings, each wing having a root, substantially the entire width of which extends along the corresponding side of said V-shaped neckline, said roots being connected together at the vertex of the V-shaped neckline, the inner edges of said wings rising vertically in the flattened garment along the midsection of the front panel and the outer edges of said wings rising obliquely from substantially the inner or neckline end of the corresponding connection between the upper edges of the panels, said wings being of length such as to admit of tying their ends together at the back of the neck.

4. A lady's garment of the character described having a front presenting a V-shaped neckline, a pair of substantially pointed wings unitary with the front, each wing having a root extending from the vertex of said trough to the side of the neck, each of said wings having an inner edge along a slight ogee curve, said inner edges extending generally upward from said vertex in substantial juxtaposition when the garment is laid flat, the outer edge of each wing being substantially straight for the major part of its length and having a curved connection near its root end to the side of the neck, said wings being of length such as to admit of tying their pointed ends together at the back of the neck.

5. A lady's garment of the character described, comprising a back panel, and a front panel having sleeve openings therebetween, lines of stitching laterally connecting substantially the height of said panels other than said sleeve openings, lines of stitching connecting the upper edges of said panels to form shoulder seams, said front panel when extended flat presenting a pair of wedge shaped wings, each wing having a substantially vertical ogee curved edge rising from and, being joined at the mid-section of the front panel and having outer edges rising obliquely from the neck end of the respective shoulder seams and forming an acute angle with the inner upright edge.

6. A lady's garment of the character described, comprising a back panel, and a front panel having sleeve openings therebetween, said panels being laterally stitched together along substantially the height thereof other than said sleeve openings and being further stitched together at their upper parts to form shoulder seams, the flattened extended front panels each having an upwardly directed wedge shaped wing, said wings in the flattened extended garment having continuous upright edges rising from the mid-point of the front panel which determines the vertex of a V-neck, and having oblique outer edges curved

inward from the neck end of the respective shoulder seams and thence directed obliquely upward to an acute apex with respect to the corresponding inner upright edge, the extremities of the upright edges of the wedge shaped wings being nearly equidistant from the neck end of the corresponding shoulder seam.

7. The combination recited in claim 6 in which the width of the root of each wing extending from the inner or neck end of the shoulder seam to the vertex of the V-neck is in the order of one foot, the length of the upright edge of each wedge is in the order of 18 inches and the angle of the V-neck is about 7 inches below the inner or neck end of the shoulder seam.

8. The combination recited in claim 6 in which each wedge shaped wing has a liner section of the same material as the blouse, stitched to the inner and outer edges of the entire length of said wedge shaped wing.

9. A lady's garment of the character described, comprising a one-piece back panel, a front panel comprising two identical blanks vertically stitched together along their mid-line to the base up to the neckline of the blouse, each of said front panels having integral therewith an upstanding wedge shaped wing rising when the garment is laid flat, substantially vertically along the inner edge of said wing from the mid-seam, each of said wings having an outer oblique edge at an acute angle with the upright edge and curved outwardly at its root edge continuous with the neck end of the corresponding shoulder seam.

10. A lady's garment of the character described, comprising a back panel, a pair of bias-cut front panels stitched together along the vertical mid-line of the garment, said garment having a V-neck line, said vertical mid-line terminating at the vertex of said neckline, each of said front panels having a wing unitary therewith, each of said wings having its root extending obliquely from the said vertex to the side of the neckline, the inner edges of said wings extending substantially upward from said mid-line in juxtaposed relationship when the garment is laid flat upon a table, the outer edges of said wings being substantially straight for the major portion of the length thereof and merging at their root ends with the sides of the neckline, said outer edges extending at an acute angle with respect to said inner edges for a pointed tip of each wing, said wings being of length such as to admit of being tied together at their pointed ends about the back of the neck.

CHARLOTTE GOLDSTEIN.
